UNITED STATES PATENT OFFICE

CHARLES G. SMITH, OF MEDFORD, MASSACHUSETTS, ASSIGNOR, BY MESNE ASSIGNMENTS, TO RAYTHEON INC., OF CAMBRIDGE, MASSACHUSETTS, A CORPORATION OF MASSACHUSETTS

ELECTRICAL APPARATUS

Application filed July 30, 1923, Serial No. 654,645. Renewed October 21, 1930.

The present invention relates to electrical apparatus and more particularly to types of electrical apparatus involving electrical conduction through a gaseous medium.

5 It will be appreciated by those skilled in the art that one of the chief disadvantages of the usual forms of gaseous conduction apparatus, which involve the ionization of an electrically stressed gaseous medium, lies in the fact that 55 continued operation of the apparatus causes the discharge to become irregular and erratic. This erratic operation arises partly from the formation of a layer of ionized gas adjacent the walls of the containing receptacle, the action of this ionized gas being to 60 electrically charge the receptacle at various points, thus giving rise to non-uniform and varying potential gradients throughout the gaseous region. Furthermore, continued 65 discharge in the region adjacent the walls of the receptacle causes the walls to become blackened or covered with a layer of conducting material, the formation of which tends not only to aggravate the erratic operation of the device; but also after long 70 continued use, to often render the device practically inoperative.

The object of the present invention is to provide improvements in gaseous conduction devices of this general nature whereby 75 regular and uniform operation of the apparatus may be secured.

In the usual constructions of gaseous discharge apparatus it has been found that the 80 undesirable electrical charging of the receptacle arises from the fact that electrostatic lines of force which may be enabled to pass near the walls of the receptacle ordinarily lie within a gaseous region of considerable 85 magnitude. The presence of electrostatic lines of force in a large gaseous region causes ionization of the gas, from which follow the charging of the receptacle and the consequent disadvantages outlined above. With 90 the above object in view, however, I have discovered, that by restricting the gaseous region through which such lines of force may pass, gaseous ionization in this region may be substantially eliminated. Accordingly, 95 90 one feature of the present invention contem-

plates the provision of an electrical apparatus having electrodes so maintained in a gas filled receptacle that the gaseous regions adjacent the walls of the receptacle are of such restricted dimensions that ionization is impossible. To this end, the width of such restricted gaseous regions should be comparable to the means free path of electrons in the gas, that is so short that electrons traveling directly across such regions 100 produce insufficient ionization to initiate substantial conduction. The mean free path of electrons, as herein connoted, is the average distance traveled by electrons without ionizing impact with gas molecules (or atoms).

It is believed that by the restriction of the gaseous region adjacent the walls of the receptacle, the operation of the present invention depends largely upon the principles 70 disclosed in the co-pending patent of Smith, No. 1,545,207, granted July 7, 1925, which describes a novel type of insulating apparatus in which two electrodes are spaced so close together in a gas that gaseous ionization and consequent conduction are impossible. A gaseous region of such restricted magnitude may be said to present a practically infinite electrical resistance. It is therefore believed that the same principle 75 holds in the present invention in which the electrostatic lines of force are constrained to pass through restricted gaseous regions.

Other features of the invention consist of certain novel features of construction, 80 combinations and arrangement of parts hereinafter described and claimed, the advantages of which will be apparent to those skilled in the art from the following description.

The accompanying drawing illustrates the preferred form of a gaseous conduction tube embodying the several features of the present invention.

Although the features of the present invention are applicable to substantially any type of gaseous conduction apparatus, the illustrated embodiment of the invention employs the type of apparatus described in the co-pending patent of Smith, No. 1,617,179, 100

granted Feb. 8, 1927. This application discloses a novel type of rectifying device comprising two electrodes spaced apart in a gas, one of the electrodes being provided with a hollow space in which is permitted the formation of a space charge of positive ions. Such a tube is conducting when the hollow electrode acts as cathode but is insulating for voltages in the opposite direction. Accordingly, the illustrated embodiment of the present invention comprises anode and cathode assemblies, the cathode being provided with a hollow space to permit the formation of a spaced charge of positive ions. The electrode assemblies are conveniently supported upon a reentrant stem of the insulating receptacle and are preferably so constructed that the anode assembly is entirely surrounded by the cathode assembly, thereby preventing the discharge from affecting in any way the external part of the receptacle. However, the stem upon which the electrode assemblies are mounted is maintained in the region of a fairly intense electric field. According to the present invention, therefore, the electrodes are so mounted upon the stem that any electrostatic lines of force which pass adjacent the stem are constrained to lie within a gaseous region of such restricted magnitude that ionization is prevented.

Referring particularly to the drawing, the preferred construction comprises a receptacle 2 consisting of an external bulb 5 and a reentrant cylindrical stem 7, both being preferably of glass. The stem 7 is provided with a partition 8 of the form shown to divide the stem into two parts, the upper part communicating with the rarefied gaseous medium enclosed by the external bulb 5. The actual manufacture of the apparatus is carried out by mounting both electrode assemblies on the stem and thereafter sealing the stem to the external bulb portion after which the tube is exhausted in the usual manner. The tube may then be filled with any gas at reduced pressure but it is preferred to use an inert monatomic gas such as helium. The anode assembly comprises the anode proper 10 consisting preferably of a carbon button, a support 12 for the button, an internal cylinder 14 and an external guard cylinder 18. The two cylinders are connected by an annular supporting member 20 having a flanged surface which is adapted to rest upon the upper part of the stem. To this end, it is desirable that the upper surface of the stem should be accurately ground. In order to hold the anode assembly rigid, the upper end of the guard cylinder 18 is spun over the edge of the carbon button 10, as indicated in the drawing. The supporting member 20 has a depending cylindrical portion 21 which is adapted to fit snugly against the internal surface of the stem and an upstanding cylindrical portion 22 which is attached to the

guard cylinder 18 in a manner to maintain the lower portion of the guard cylinder at a slight distance from the outer surface of the stem 7. This distance should be of the order of magnitude of the mean free path of electrons in the gas. The anode assembly is maintained upon the stem by means of a helical spring 23 connected between the support 12 and a lead wire 15 which is sealed in the partition 8 in the usual manner. The cathode assembly includes the cathode proper which is constructed with a base portion 30 having an upstanding sleeve 32 communicating with a hollow space enclosed by the hollow cylindrical portion 34. The base 30 and the portion 34 are preferably constructed of carbon. The base 30 rests upon a flange 36 of a cathode guard cylinder 38 which is of such dimensions that its internal surface is spaced from the surface of the anode guard cylinder 18 by a distance which is so short that ionization between the two guard cylinders is impossible. The two parts of the cathode are connected together and supported upon the flange 36 by a flange member 40 to which a suitable wire 41 is soldered at diametrically opposite points, the wire being adapted to pass over the hollow portion 34 of the cathode. The guard cylinder 38 is supported upon a guard ring 42 which is in contact at its lower end with the stem 7 and which is provided with a recess 44 at its upper end, this recess being comparable in width to the distance separating the stem 7 and the guard cylinder 18. Also the upper end of the guard ring 42 is spaced from the lower end of the guard cylinder 18 by an equally short distance. According to the invention disclosed in the co-pending Patent No. 1,617,179, the parts are so disposed that the surfaces of the anode 10 and the cathode base 30 are also separated by a distance which is comparable to the mean free path of electrons in the gas. The cathode assembly is rigidly maintained on the stem by means of a cylindrical member 46 which is provided with a flange to which the guard ring 42 may be secured, as indicated in the drawing. The cylindrical member 46 is secured to the stem 7 by a suitable clamp member 48. A cathode lead wire 16 is attached to any part of the cathode assembly. After the reentrant stem 7 and the external bulb 5 are sealed together to form the completed tube 2, a threaded base 50 of the usual form is secured to the lower part of the tube, the lead wire 15 being connected to one terminal of the base and the lead wire 16 to the other.

The simple rectifying circuit shown in connection with the apparatus includes an alternating current generator 52, a transformer 54, the tube 2, and a suitable load, all connected as indicated.

It will be seen that inasmuch as the anode assembly is entirely surrounded by the cath-

ode assembly, the external bulb portion of the tube cannot be injuriously affected in any way by the discharge. The close spacing between the guard cylinders 18 and 38 renders discharge impossible except between the active surfaces of the electrodes themselves. Furthermore, the glass stem 7 is not placed under an excessive electrical stress since the path afforded for electrical conduction 10 through the glass extends from the supporting member 20 to the lower part of the guard ring 42 and may thus be made sufficiently long to prevent any injurious effects within the glass itself. According to the present invention, the lower portion of the guard cylinder 18 and the upper part of the guard ring 42 are each separated from the material of the stem 7 by such a short distance that any electrostatic lines of force which may pass 15 within the included region are powerless to initiate ionization.

Although the illustrated embodiment of the invention is designed to prevent undesirable discharge adjacent the surface of the reentrant stem, it is understood that the stem is to be considered as part of the containing receptacle and that the walls of the receptacle, as that term is used herein and in the appended claims, are to be considered as including the surfaces of the stem or any other parts of the receptacle adjacent which any electrostatic lines of force may pass.

This application is in part a continuation of my Patent #1,617,179, granted February 8, 1927.

The invention having been described, what is claimed is:

1. A gaseous discharge rectifier comprising a sealed container having a reentrant stem, said stem having a cylindrical portion extending inwardly into said container, a cathode and anode mounted on said stem in spaced relation to each other, one of said electrodes being supported by concentric metal cylinders, the distance between which is substantially equal to the thickness of the cylindrical portion extending from said stem, said concentric members being mounted respectively on the inside and outside of said projecting portion, an annular member anchored between said concentric members and serving as a stop for the edge of said projecting portion and a spring connected to said electrode and serving as a lead therefor, pulling said electrode down to maintain said concentric members firmly against said projecting portion.

2. A gaseous discharge rectifier comprising a sealed container having a reentrant stem, said stem being provided with a cylindrical portion projecting inwardly, a cathode and an anode spaced apart therein and mounted on said stem, both electrodes being supported by concentric cylindrical metallic members, said anode being supported by two

such members engaging the inside and outside walls respectively of said projecting portion of said stem, an annular member between said anode supporting concentric members, joining said members and serving as a stop for the edge of said projecting stem portion, and a spring connected to the anode and serving as a lead therefor, pulling said anode, and said anode supporting concentric members downwardly into firm engagement with said projecting stem portion. 75

3. A gaseous discharge device comprising a sealed container having a reentrant stem, said stem having a hollow portion extending inwardly into said container, two electrodes 80 mounted on said stem in spaced relation to each other, one of said electrodes being supported by metallic members, said members being mounted respectively on the inside and outside of said hollow portion, a member 85 fastened between said metallic members and serving as a stop for the edge of said hollow portion, and means for maintaining said last named electrode and its supporting members on said hollow portion. 90

4. A gaseous discharge device comprising a sealed container having a reentrant stem, said stem having a hollow portion extending inwardly into said container, two electrodes mounted on said stem in spaced relation to 95 each other, one of said electrodes being supported by metallic members, said members being mounted respectively on the inside and outside of said hollow portion.

5. A gaseous discharge device comprising 100 a sealed container having a reentrant stem, said stem having a hollow portion extending inwardly into said container, a cathode and an anode supported on said stem, said anode being supported by a supporting member on 105 said hollow portion, a projection on said supporting member engaging a shoulder on said hollow portion, and means for holding said anode and supporting member with said projection against said shoulder. 110

6. A gaseous conduction device comprising a hollow cathode with an opening therein, an anode having a surface presented to the interior of the cathode through said opening, a sealed container having a reentrant stem, said stem having a hollow portion extending inwardly into said container, a supporting member for said anode engaging the outside and inside of said hollow portion, said cathode being supported from 115 120 said stem in spaced relationship to said anode.
